UNITED STATES PATENT OFFICE.

SOLOMON RICHTER, OF MARTIN, PENNSYLVANIA.

COKE-DRAG.

941,385.

Specification of Letters Patent. Patented Nov. 30, 1909.

Application filed March 29, 1909. Serial No. 486,471.

To all whom it may concern:

Be it known that I, SOLOMON RICHTER, a citizen of the United States, residing at Martin, in the county of Fayette and State 5 of Pennsylvania, have invented certain new and useful Improvements in Coke-Drags, of which the following is a specification.

My invention relates to a device adapted to be inserted into coke ovens, or the like 10 situations, to draw out coke or other material, and particularly to a device having a jaw which is opened when the drag is inserted into the oven, but which automatically closes as the drag is withdrawn.

15 My invention also comprises a device of the character described, having a front scraper and a rear scraper, the front scraper being so connected to the pivoted jaw that when the drag is withdrawn, the rear scraper 20 will be raised so as to collect any coke or other material which may have fallen upon the floor of the oven.

For a full understanding of the invention and the merits thereof, and to acquire a 25 knowledge of the details of construction, reference is to be had to the following description and accompanying drawing, in which:

Figure 1 is a side elevation of my improved scraper with its jaw in open position; Fig. 2 is a like view with the jaw closed; Fig. 3 is a plan view with parts in the position shown in Fig. 1; and, Fig. 4 is a transverse section on 4-4.

Corresponding and like parts are referred 35 to in the following description and indicated in all the views of the drawing by the same reference characters:

In the embodiment of my invention shown in the drawing, 2 designates opposed side 40 pieces of any suitable material, preferably of stiffened sheet metal. The front ends of the side pieces are downwardly and forwardly inclined and provided with a downwardly and forwardly inclined scraper 3 45 which extends transversely across the entire drag. The rear ends of the side pieces 2 are downwardly and rearwardly inclined, and at their rear ends are pivoted to the lower edge of a rear scraper 4. The rear 50 scraper 4 is slotted, as at 5, for the passage of a draft bar or operating rod 6 by which the scraper is to be handled. The forward end of this operating rod 6 is adapted to abut against a post 7 which projects rear- 55 wardly from the front scraper 3 in such position that when the scraper is pushed into

the oven, the rod 6 will be in alinement with the post 7. Pivotedly mounted in the forward end of the operating rod 6 is a crank 8 whose arms 9 are supported in bearings 10 60 in the upper edges of the side pieces 2. The arms 9 are there provided with upwardly turned bell crank arms 11, so that as the crank 8 is turned by drawing upon the operating rod 6, the arms 11 will be likewise 65 turned. The upper ends of the arms 11 are pivotally attached to link bars 12 whose rear ends are pivotally connected to the rear or upper edge of the scraper 4 at 13. This pivotal attachment is best secured by providing the upper edge of the scraper 4 with a rod 14 which reinforces the upper edge of the scraper and provides bearings for the ends of the links 12. The forward ends of the links 12 are connected to a transverse 70 jaw 15 having downwardly turned teeth 16.

From the construction described, it will be seen that when the scraper is pushed into the oven, the operating rod 6 will be advanced until it strikes the end of the post 7, 80 and that in this position, the crank 8 will be so turned as to elevate the jaw 15 and the links 12. The front of the drag formed by the end plate 3, is inclined so as to allow coke or other materials to easily pass up the 85 incline and into the space behind the scraper 3, thus filling the drag. As the operating rod is drawn open to withdraw the drag, the crank 8 will be turned reversely, thus depressing the jaw 15 into contact with the 90 upper end of the scraper 3, and this movement will at the same time lift the rear end plate or scraper 4 which is pivoted as at 17 to the rear ends of the side pieces 2. This scraper will then act to collect any 95 pieces of coke or coal which may have fallen upon the floor, and will carry these pieces ahead of the drag as it is withdrawn.

While I have shown the drag as being formed without a bottom plate, it is obvious 100 that a bottom plate might be used without in any way departing from the spirit of the invention.

I do not wish to be limited to the details of construction, for the reason that the principles thereof might be embodied in a number of different forms, without departing from the principles of the device.

Having thus described the invention, what is claimed as new is:—

1. A drag of the character described, comprising side pieces, a pivoted jaw, a longi-

tudinally shiftable operating rod, a crank upon the forward end of the operating rod, and links attached one to either end of the crank and connected to the jaw.

5. 2. A drag of the character described, comprising side pieces and a front scraper attached to the side pieces, a longitudinally shiftable operating rod, a crank connected to the forward end of the operating rod and 10 having upwardly extending arms, links pivoted to the arms, and a jaw carried by the said links.

3. A drag of the character described, comprising side pieces, an end piece pivoted to 15 the rear ends of the side pieces, a front scraper attached to the forward ends of the side pieces, a longitudinally shiftable operating rod, a crank connected to the operating rod and having upwardly extending 20 arms, and a jaw having rearwardly extending link rods pivoted to the rear end piece of the scraper and to the upwardly extending crank arms.

4. A drag of the character described having a frame provided with a front scraper, a 25 movable jaw coacting therewith, an operating rod longitudinally shiftable with relation to the front scraper and frame, and a connecting member between the operating 30 rod and the movable jaw, said connecting member being pivoted at its middle to the frame, whereby upon a rearward draft upon the operating rod the connecting member shall be rotated to throw the jaw forward 35 and downward against the front scraper, and upon a forward movement of the operating rod the connecting member shall be rotated to lift the jaw from the scraper.

5. A drag of the character described, including a front scraper having a rearwardly 40 extending post, a longitudinally shiftable operating rod adapted to abut against said post, a crank mounted on the operating rod, and a jaw pivotally connected to said crank 45 to be moved into engagement with the scraper when the operating rod is drawn rearward.

6. A drag of the character described, comprising side pieces, an inclined forward 50 scraper attached to the side pieces, a rearwardly projecting post mounted on the scraper, a rear scraper pivotally connected to the rear ends of the side pieces, said scraper being slotted at its middle, an operating 55 rod passing through said slot and having its forward end in alinement with

the post, a crank connected to said operating rod and having its ends supported in bearings on the side pieces, upwardly extending arms at the extremities of said 60 crank, a jaw located to engage with the upper end of the forward scraper, and rearwardly extending link rods formed with said jaw pivoted at their middles to the upwardly extending arms of the crank and at 65 their rear ends pivotally attached to the free edge of the rear scraper.

7. A drag of the character described having a frame formed with a front scraper, a 70 jaw pivotally mounted to close against said front scraper, an operating rod having a limited movement with relation to the frame and scraper, and a connecting member between the jaw and operating rod, said connecting member being pivoted at its middle, 75 thus giving reverse movements to the operating rod and jaw respectively, thereby automatically opening and closing the jaw as the operating rod is moved forward or rearward.

8. A drag of the character described, having a frame, a forward scraper attached to the same, a jaw pivotally connected to the frame and adapted to close upon the forward scraper, a longitudinally movable operating rod connected to the jaw to close the same upon a rearward movement of the rod and open the same upon a forward movement thereof, and a stop on the drag 85 with which the operating rod engages at 90 the termination of its forward jaw-opening movement.

9. A drag of the character described, having side pieces, a fixed rearwardly and upwardly inclined scraper at its forward end, 95 a pivoted scraper at its rear end, an operating rod passing through the pivoted scraper, engageable at the end of its forward movement with a stop on the frame, and a movable jaw having connection with the operating rod, whereby it shall be moved down against the face of the scraper upon a rearward movement of the operating rod and lifted from said scraper upon a forward movement of the same.

In testimony whereof I affix my signature in presence of two witnesses.

SOLOMON RICHTER. [L. S.]
